United States Patent Office

Des. 224,136

Patented July 4, 1972

224,136

PLATE OR THE LIKE

Gregory Mirow, Corning, N.Y., assignor to Corning
Glass Works, Corning, N.Y.

Filed Dec. 4, 1970, Ser. No. 26,282

Term of patent 14 years

Int. Cl. D7—01

U.S. Cl. D44—15

The figure is a top plan view of a plate of conventional configuration showing my new design.

I claim:

The ornamental design for a plate or the like, as shown and described.
